US0D1070850S

(12) **United States Design Patent** (10) Patent No.: **US D1,070,850 S**
(45) Date of Patent: ** Apr. 15, 2025

(54) **SMART WATCH**

(71) Applicant: **Creek Wearable Technology Co., Ltd.**, Shenzhen (CN)

(72) Inventors: **An He**, Shenzhen (CN); **Kexin Tong**, Shenzhen (CN); **Yichen Tan**, Shenzhen (CN)

(73) Assignee: **Creek Wearable Technology Co., Ltd.**, Shenzhen (CN)

(**) Term: **15 Years**

(21) Appl. No.: **35/519,903**

(22) Filed: **Jan. 9, 2024**

(80) **Hague Agreement Data**

Int. Filing Date: **Jan. 9, 2024**

Int. Reg. No.: **DM/234662**

Int. Reg. Date: **Jan. 9, 2024**

Int. Reg. Pub. Date: **Feb. 2, 2024**

(30) **Foreign Application Priority Data**

Nov. 28, 2023 (CN) 202330779219.6

(51) **LOC (15) Cl.** **14-02**

(52) **U.S. Cl.**

USPC **D14/344**
